UNITED STATES PATENT OFFICE.

CHRISTER PETER SANDBERG, OF LONDON, ENGLAND.

SLEEPER FOR PERMANENT WAY.

1,183,678.

Specification of Letters Patent. Patented May 16, 1916.

Application filed July 12, 1915. Serial No. 39,397.

To all whom it may concern:

Be it known that I, CHRISTER PETER SANDBERG, a subject of the King of Great Britain, residing in London, England, have invented 5 certain new and useful Improvements in Sleepers for Permanent Way, of which the following is a specification:

It has been proposed to make a steel railway or tramway sleeper with jaws for the 10 rails in one piece with it, by stamping or cutting tongues of the metal and turning these tongues upward and toward each other to form the jaws. A bar or plate of steel of thickness suitable for constituting 15 the sleeper would not furnish tongues of sufficient rigidity to constitute the jaws. It has therefore been proposed to make the bar or plate of increased thickness at those places where the tongues are to be cut, so 20 that the latter may be of thicker cross section than the sleeper. It is difficult, however, to roll a bar or plate of section that is not uniform throughout and the expense involved in doing so makes the suggestion 25 impracticable. It has further been proposed to make a steel sleeper with longitudinal ribs on the under side and to turn up the end of such a sleeper to form a clip or jaw for the rail, the other clip or jaw being 30 bolted or riveted to the sleeper.

By my invention the plate or bar forming the sleeper is provided with one or more relatively deep longitudinal ribs on that face which is the under side in use and tongues 35 are cut or stamped out of the material of the sleeper and turned upward and toward one another, the position of the rib or ribs on the face of the sleeper being such that when the tongues are turned up to form the 40 jaws they have this rib or these ribs on their outer surfaces and are thus sufficiently strong to hold the rail and to permit a key of any suitable kind being driven in between one jaw and the web of the rail. This 45 mode of providing the necessary substance in the jaws has the advantage that the sleeper is rolled of the same section throughout, and the further advantage that the rib or ribs serve to anchor the sleeper to the 50 ballast, being of sufficient depth for the purpose. It also permits of the sleeper being of greater length than the distance between the jaws so that it is thoroughly supported on the ballast and can carry heavy loads. 55 Moreover, the rib strengthens the sleeper and thus permits of a shallower trough sec-

tion for the latter, a result of importance in consideration of the difficulty in packing modern ballast beneath a sleeper of deep trough section.

The invention is applicable to any form of jaw. The tongues may be of the normal form for a chair, that is to say one of the jaws may be turned inward to form an abutment for the web of the rail as in the standard chair, while the other together with the web of the rail constitutes the key-way.

With flanged rails the jaws may both be straight or slightly curved, the abutment being provided by a distance piece or key 60 between the jaw or each jaw and the web of the rail. Or the jaws may be of the short form for clipping the flanges, with or without the insertion of a key between one or each jaw and the flange.

The invention is of course applicable whether the jaw is constituted by a single tongue or by two or more tongues turned up side by side.

The accompanying drawings illustrate 80 two forms of jaws, Figure 1 being a side elevation and Fig. 2 a plan of one form and Figs. 3 and 4 like views respectively of the other form. Fig. 5 is a section on line 5—5 of Fig. 1 drawn to an enlarged scale and shows in dotted lines the form of the sleeper after the rolling operation, before 85 it is bent to the trough shape shown in full lines. In both forms the sleeper *a* has a deep mid-rib *b* (Fig. 5) on its under surface.

In Figs. 1 and 2 the jaws *c* are cut from the metal by suitable punches and turned up to form angles slightly less than a right angle with the surface between them; thus 95 the rib *b* is on their outer faces. The rail is held in place by a metal distance piece *d* and by a key *d'*. In this case the necessary lateral inclination of the surface of the rail is given by slightly inclining the sleeper in 100 an upward direction outwardly for a certain portion of its length at the place where the jaws are situated.

In Figs. 3 and 4 the tongue *e* is shaped to form an abutment for the web of the rail, as in the normal chair. The tongue *e* embraces or fits over the foot of the rail and terminates in an up-turned part which is presented against the web and engages the web with its face, such engagement commencing as close to the bottom of the web as possible. The lateral inclination is ob-

tained by inclining the metal between the jaws in the necessary direction, as shown.

Having thus described the nature of the said invention and the best means I know of carrying the same into practical effect, I claim:—

5. 1. A steel railway or tramway sleeper having jaws for holding the rails and having a relatively deep anchoring rib on the under face, in which the jaws are formed of tongues cut from the metal of the sleeper and have a portion of the rib on their outer faces.
10. 2. A steel railway or tramway sleeper having a relatively deep anchoring rib on its under face and having jaws for holding the rails turned up toward one another from the metal of the sleeper with a portion of the rib on their outer faces.
15. 3. A steel railway or tramway sleeper of the kind having jaws constituted by tongues of the metal turned upwardly and toward each other, wherein the sleeper extends at its ends some distance beyond the jaws and
20. 25. has a relatively deep anchoring rib on its under surface which is continued up the outer surfaces of the jaws, for the purpose of strengthening the latter.
25. 30. 4. A steel railway or tramway sleeper having a relatively deep anchoring rib and jaws for holding the rail turned up from the metal of the sleeper and reinforced by ribs

on their outer faces in which the jaws provide a chair wherein the rail is held by the coöperation with one of said jaws of a wedge 35 interposed between it and the rail web.

5. A steel railway or tramway sleeper having a relatively deep anchoring rib and jaws for holding the rail turned up from the metal of the sleeper and reinforced by ribs 40 on the outer faces, in which one of the jaws is bent inward to directly engage with its face the web of the rail and the other jaw is turned upward to hold a wedge engaged between said jaw and the web of the rail. 45

6. A steel railway or tramway sleeper having a relatively deep anchoring rib and jaws for holding the rail turned up from the metal of the sleeper and reinforced by ribs 45 on the outer faces in which one of the jaws is bent inward to embrace, without engaging, the foot of the rail and to directly engage with its face the web of the rail from near the bottom upward and the other jaw is turned upward to hold a wedge engaged 50 between said jaw and the web of the rail. 55

In testimony whereof I have signed my name to this specification in the presence of two subscribing witnesses.

CHRISTER PETER SANDBERG.
